UNITED STATES PATENT OFFICE.

JAMES T. STEWART, OF PHILADELPHIA, PENNSYLVANIA.

IMPROVEMENT IN TUCK-CREASERS FOR SEWING-MACHINES.

Specification forming part of Letters Patent No. 137,108, dated March 25, 1873.

To all whom it may concern:

Be it known that I, JAMES T. STEWART, of the city and county of Philadelphia, and State of Pennsylvania, have invented new and useful Improvements in Tuck-Markers; and I do hereby declare the following to be a clear and exact description of the nature thereof, sufficient to enable others skilled in the art to which my invention appertains to fully understand, make, and use the same, reference being had to the accompanying drawing making part of this specification, in which—

Figure 1 is a top view of the device illustrating my invention. Fig. 2 is an end view partly in section. Fig. 3 is an end view opposite to that of Fig. 2. Fig. 4 is a top view of the screw-plate, and Fig. 5 is an end view of the marker.

Similar letters of reference indicate corresponding parts in the several figures.

This invention relates to improvements in tuck-markers; and consists in an adjustable arm for operating the marker. It also consists in the construction of the frame and connected parts. It also consists in the screw-plate constructed with means for securely holding the sliding parts in position thereon.

Referring to the drawing, A represents the screw-plate for attachment to the sewing-machine. B represents a plate sliding on the plate A, and above the plate B is arranged an arm, C, which is secured thereto at one end, a, its other end being free. D represents a swinging frame mounted on the arm C, and consisting of a piece of wire or other suitable material having a longitudinal portion, a', which extends parallel with the arm C, and transverse sides b, the ends of which are jointed to said arms so that the frame has fixed bearings. E represents the marking-arm, which is secured to the frame and moves with it.

In the Letters Patent granted to James S. Hugg, May 28, 1872, the swinging frame is made to slide on an elevated arm, and the marker is hinged to said arm beneath the frame. Said frame has but a single bearing, and if strained or displaced the regularity of marking is impaired, and the marker is rendered unserviceable.

F represents an operating lever, which consists of a bar or arm secured at one end to the arm C, and at a point between its ends to the portion a' of the frame D, the connections being such that the lever will slide on both the arm C and the part a' of the frame, and is thereby rendered adjustable.

Thus it will be seen in my invention that the swinging frame has a bearing at each of its ends, and the sliding operating arm or lever is connected to the rigid arm and the frame, whereby the latter is greatly stiffened and the objections heretofore stated are overcome.

G represents a spring, which is secured to the arm C, and presses against the frame D, and in connection with the sliding lever operates the marker in opposite directions. The screw-plate A is flanged on its sides, and cut away to leave passages d for the insertion of the sliding plates B and H. In order to properly hold the said sliding pieces in position I secure to the screw-plate, between its flanged sides, a confining-plate, J, which is elevated above the bottom of the screw-plate, and so arranged that its sides e and f, respectively, overhang the passages d. Now, when the sliding plates are in position vertical displacement thereof is prevented by the plate J. A vertical screw, g, is passed through the plate J, and, bearing against the plate or gage H, prevents longitudinal displacement thereof. A horizontal screw, h, is passed through the flanged end j of the plate A, and is designed to hold in position the plate B, which carries the marking mechanism.

Owing to the light material of which sewing-machine attachments generally are made the screw h, pressing continuously against the plate B, may cause the latter to bear upward and be gradually forced from its seat on the screw-plate; but here the overhanging end of the confining-plate performs an important part by resisting the upward tendency of the plate, and consequently holds the latter firmly in place.

Having thus described my invention, what I claim as new, and desire to secure by Letters Patent, is—

1. The operating-lever F connected to and sliding on both the supporting-arm C and

frame D, substantially as and for the purpose described.

2. The frame D supported at both ends on the arm C, in combination with the marker E fixed to the frame and the operating-lever F sliding thereon, substantially as and for the purpose described.

3. In combination with the screw-plate A, the elevated and overhanging plate J and the

screws g and h, to operate with the sliding pieces B and H, and hold them in position, as set forth.

The above signed by me this 17th day of August, 1872.

JAMES T. STEWART.
